[57] CLAIM

The ornamental design for a housing for a portable handset telephone or similar article, as shown and described.

DESCRIPTION

FIG. 1 is a top, front and left side perspective view of housing for a portable handset telephone or similar article showing our new design;

FIG. 2 is a left side elevational view thereof, the side opposite being a mirror image;

FIG. 3 is a rear elevational view thereof; and FIGS. 4 and 5 are respectively top and bottom plan views thereof.

The broken line showing of environmental keyboard panel arrangement in FIG. 1 is for illustrative purposes only and forms no part of the claimed design.

FIG. 2

FIG. 1

FIG. 3

FIG. 4

FIG. 5
